(57) **CLAIM**

I claim an ornamental design on a columbarium, as shown and described.

DESCRIPTION

FIG. 1 is a front elevational view of a columbarium showing my new design;

FIG. 2 is a bottom plan view thereof;

FIG. 3 is a top plan view thereof;

FIG. 4 is a rear elevational view thereof;

FIG. 5 is a top perspective view thereof;

FIG. 6 is a front elevational view of a second embodiment of a columbarium showing my new design;

FIG. 7 is a bottom plan view thereof;

FIG. 8 is a top plan view thereof;

FIG. 9 is a rear elevational view thereof; and,

FIG. 10 is a top perspective view thereof.
